CLAIM

The ornamental design for a combination lighter holder and bottle opener, as shown and described.

DESCRIPTION

FIG. 1 is a perspective view of the combination lighter holder and bottle opener, shown in an environment of use, according to our new design;

FIG. 2 is a front view of the combination lighter holder and bottle opener thereof, shown removed from the environment for clarity of disclosure;

FIG. 3 is a rear view of the combination lighter holder and bottle opener of FIG. 2;

FIG. 4 is a side view of the combination lighter holder and bottle opener of FIG. 2;

FIG. 5 is a side view of the combination lighter holder and bottle opener of FIG. 2;

FIG. 6 is a bottom view of the combination lighter holder and bottle opener of FIG. 2;

FIG. 7 is a top view of the combination lighter holder and bottle opener of FIG. 2;

FIG. 8 is a perspective view of the combination lighter holder and bottle opener of FIG. 1, shown in an alternative configuration of use; and,

FIG. 9 is a perspective view of the combination lighter holder and bottle opener of FIG. 2 shown in another environment of use.

The evenly spaced broken lines in the drawings depict portions of the combination lighter holder and bottle opener that form no part of the claimed design. The additional broken lines in FIGS. 1 and 9 illustrate environmental subject matter only and form no part of the claimed design.
